WATER RESERVOIR FOR COOKING STOVES

William P. Biddle, Jr., Knoxville, Tenn., assignor
to Sandebond Patents, Inc., Knoxville, Tenn., a
corporation of Delaware

Application May 13, 1943, Serial No. 486,866

1 Claim. (Cl. 126—34)

This invention relates to an improvement in water reservoirs for cooking stoves, and particularly to a reservoir applied as an attachment to a cook stove, as distinguished from being "built-in" within the interior thereof.

Heretofore the conventional position of the water reservoir has been to incorporate it within the stove at one end thereof. It has been proposed also to provide a reservoir at the rear of the top of the stove, but in such latter suggestions, the usual procedure has been to construct the stove pipe as an independent element separate from the wall of the water reservoir which must receive its heat from the products of combustion in the stove. In some instances, the stove pipe has been counter-sunk in the back of the stove, and in other instances, an air space is provided between the wall of the smoke pipe adjacent to the water reservoir and the contiguous surface of the water reservoir which is to obtain its heat from the products of combustion. These various designs are expensive in construction, use additional material that should not be required, and are not efficient in the heating of the water in the reservoir.

The principal objects of this invention are: first, to reduce the cost of the construction of the reservoir for heating water on an ordinary range; second, to increase the efficiency of the transfer of heat from the products of combustion to the water reservoir; third, to avoid substantially increasing the depth of the stove rearwardly, particularly at the back edge of the stove top, over what would be required for a smoke pipe at the back; and, fourth, to restrict the dimension of this depth without counter-sinking the stove pipe into the rear of the stove.

These objects are accomplished by constructing the water reservoir and the smoke pipe chamber as one integral construction having a single thickness wall separating the smoke pipe from the water reservoir, and with the reservoir located immediately beside the smoke pipe and of substantially equal depth therewith, all built in a substantially flat rectangular chamber located immediately at the back of the stove. By this construction, using a wall common to the smoke pipe and water reservoir, a substantial saving of material is effected by reducing to a minimum the thickness of the metal between the smoke pipe and water reservoir, thereby obtaining a maximum transfer of heat from the products of combustion in the smoke pipe to the water in the reservoir. There is no air gap present nor other means that would provide substantial insulation

therebetween. This construction is provided without modifying the stove construction by counter-sinking the stove pipe in the back of the stove top or otherwise, and it locates the back upright wall of the water reservoir substantially in line with the back upright wall of the smoke pipe itself. All of this effects simplicity of design, reducing the cost to a minimum, while accomplishing a most efficient heating of the water.

A preferred embodiment of the invention is shown in the accompanying drawing, in which:

Fig. 1 is a top plan view of a cooking stove having this improved water reservoir applied thereto;

Fig. 2 is an end elevation thereof; and

Fig. 3 is a rear elevation thereof, parts being broken away and in section.

The invention is shown as applied to a cooking stove of well-known commercial form designated generally by the numeral 1, being of the type known as coal or wood-burning range. This stove has a fire box at one end thereof, as indicated at 2, from which the products of combustion circulate under the cooking top of the range and are discharged through a smoke outlet 3 at the back thereof below the top of the range.

The water reservoir construction is shown as an attachment mounted at the back of the range, flat against the rear wall thereof. This structure includes both a water reservoir 4 and a smoke pipe or heat dissipating chamber 5, located in side-by-side relation. These chambers 4 and 5 are enclosed within front and back walls 6 and 7, respectively, and end walls 8 and 9, and a bottom 10. The walls 6—10 are preferably constructed of sheet metal, relatively thin, and fashioned in a substantially flat integral structure, by welding or otherwise securing the sides and bottom together through liquid and air tight seams in one enclosed structure. This structure is divided lengthwise by a vertical partition 11, of single sheet metal thickness, integrally secured by welding or otherwise at its opposite edges to the faces of the walls 6 and 7. The partition 11 separates the structure into the chambers 4 and 5, and cooperates with the wall structure to form the water reservoir and the smoke pipe or chamber. The top of the reservoir structure is provided with a door opening 12, normally adapted to be closed by a removable cover, while the top of the smoke pipe 5 has a smoke pipe ring 13 adapted to receive the conventional smoke pipe.

The forward wall 6 of the reservoir structure is shown as having an opening therein, at or near the bottom of the smoke pipe 5, to interfit with the flange surrounding the smoke outlet 3

of the stove, so as to support one end of the water reservoir structure thereon, the opposite end being seated upon a bracket 14 secured to the rear wall of the range 1. If the reservoir structure is raised slightly above the smoke outlet 3, the inlet opening for the pipe 5, may be provided directly in the bottom of the latter.

The reservoir may be provided with any suitable or usual provision, such as a faucet, for draining the water from the chamber 4.

The drawing shows the reservoir chamber as located only on one side of the smoke pipe chamber 5, but if more water is to be heated, a similar water reservoir can be placed on the opposite side of the smoke pipe chamber and formed in one integral structure therewith, whereby the walls would extend continuously to both opposite sides of the smoke pipe, and be separated by two partitions into two water reservoirs with a single smoke pipe therebetween. In that event, the substantially rectangular box at the back of the stove is divided into three substantially rectangular sections, one of which provides a substantially rectangular portion through which the smoke passes from the back of the stove to the conventional circular stove pipe attached at the top of the rectangle to convey the gases of combustion to the chimney.

It will be evident that the smoke will be discharged from the stove 1 through the smoke outlet 3, directly into the lower end of the smoke pipe 5, through which the smoke would pass upwardly to the conventional smoke pipe surmounted thereon at the ring 13. In passing through the smoke pipe 5, the products of combustion would radiate heat through the single partition 11 separating this smoke chamber from the water reservoir 4, which is thin and accomplishes an effective heat transfer from the products of combustion to the water in the reservoir. This will be entirely sufficient to heat the water in the reservoir to the desired temperature, as has been demonstrated by actual test and use in commercial construction.

At the same time, the simplified design and relatively flat rectangular shape of the reservoir structure, disposes the water reservoir chamber at the rear of the stove flat against the back wall thereof where it requires no additional space over that necessary for the smoke pipe at the back of the stove, since the reservoir is built of the same depth from front to back as the smoke pipe itself, and having its back wall substantially in transverse alignment with the back upright wall of the smoke pipe. This simplicity of construction reduces the cost of manufacture to a minimum and yet is highly efficient in providing a water reservoir which does not require modification of the stove structure. Its commercial manufacture has demonstrated that it fulfills the requirements, inasmuch as it has met with great favor in the trade. At the same time it can be sold at a lower price than conventional designs of water reservoirs.

I claim:

In a cooking stove, the combination with a cooking structure having a fire box therein with a smoke outlet through the back wall of said cooking structure, of a water reservoir comprising an elongated relatively flat enclosed one-piece structure, said reservoir structure having enclosing sides extending continuously from end to end of said reservoir structure, end walls and bottom, and being of uniform width from end to end of said reservoir structure, and a partition formed of a single sheet of heat conducting material extending between the opposite sides and rigidly secured to said sides adjacent an end of said structure and separating said structure into water and smoke chambers in heat conducting relation through said partition, said smoke chamber having an opening therein adjacent the bottom thereof registering with the smoke outlet of the cooking structure and having a smoke outlet at the top thereof.
